UNITED STATES PATENT OFFICE.

HENRY J. SMITH, OF PITTSBURG, PENNSYLVANIA, ASSIGNOR TO BRYCE
BROTHERS, OF SAME PLACE.

DESIGN FOR TABLE-WARE.

SPECIFICATION forming part of Design No. 19,427, dated November 12, 1889.

Application filed March 28, 1889. Serial No. 305,176. Term of patent 14 years.

To all whom it may concern:

Be it known that I, HENRY J. SMITH, of Pittsburgh, in the county of Allegheny and State of Pennsylvania, have invented a new and original Design for Table-Ware, of which the following is a full, clear, and exact description, reference being had to the accompanying drawings, forming part of this specification, in which—

10 Figures 1 and 2 are perspective views of glass vessels provided with my design.

Like symbols of reference indicate like parts in each.

15 The design consists in a glass vessel of table-ware having at the base of the hollow body portion thereof a peripheral series of projecting bosses, which are partly above and partly below such body portion.

20 In the accompanying drawings, 2 is the body of the vessel, and 3 are projecting spherical knobs or bosses arranged in series around the vessel at the base thereof. These knobs or bosses are partly above the base-line

of the body portion 2 and partly below it, so as to impart to them the appearance of pendant knobs or drops. 25

4 is a star figure within the circle formed by the knobs, having radially-directed spikes.

The design thus constituted is neat and pleasing in appearance. 30

In Fig. 1 I show the vessel provided with a foot 5 and supporting-stem 6.

I claim—

The design for table-ware, consisting in a glass vessel or bowl having at the base of its body portion a peripheral single series or belt of projecting knobs or bosses partly above and partly below the base-line of the body portion, substantially as shown and described. 35

In testimony whereof I have hereunto set my hand this 28d day of March, A. D. 1889. 40

HENRY J. SMITH.
